F. O. ALBERTSON,
VALVE SEAT REAMER,
APPLICATION FILED DEC. 20, 1919.

1,340,359.

Patented May 18, 1920.

Inventor

F. O. Albertson

William Bradbury Atty.

UNITED STATES PATENT OFFICE.

FRANS O. ALBERTSON, OF SIOUX CITY, IOWA, ASSIGNEE TO ALBERTSON & COMPANY,
OF SIOUX CITY, IOWA, A CORPORATION OF IOWA.

VALVE-SEAT REAMER

1,340,359.

Specification of Letters Patent. Patented May 18, 1920.

Application filed December 20, 1919. Serial No. 346,377.

To all whom it may concern:

Be it known that I, FRANS O. ALBERTSON, formerly a subject of the King of Sweden, now a naturalized citizen of the United States, residing at Sioux City, in the county of Woodbury and State of Iowa, have invented a certain new and useful Improvement in Valve-Seat Reamers, of which the following is a full, clear, concise, and exact 10 description, reference being had to the accompanying drawings, forming a part of this specification.

My invention relates to an improved reamer especially adapted for the purpose 15 of cleaning and truing up the seats of internal combustion engine valve seats to secure tight fits between said seats and the puppet valves which coöperate therewith. My invention contemplates the provision of a device 20 of this class that is easy to manipulate, that is capable of being cheaply manufactured, and one which is so designed that the valve seats may be properly reamed with a minimum of damage to the cutting edges 25 of the reaming cutter or milling tool. Other advantages of the device of my invention will appear as this specification progresses.

I have found that after having been used 30 for some time, the valve seats of internal combustion engines, and more particularly the exhaust valve seats, become covered with a thin scale, coating or film that is extremely hard, so hard in fact that the valve seat can not be reamed in the usual manner without 35 considerable injury to the cutting edges of the reaming device. The formation of this hard scale or film is due, no doubt, to the pounding of the puppet valves on their seats and to the oxidizing action of the hot gasses 40 which impinge upon the seats during the operation of the engine. One of the very important features of my invention consists in the novel construction and arrangement and combination of parts, whereby this hard 45 scale or film, which forms on the valve seat, may be removed with a minimum damage to the cutting edges of the reaming device.

My invention is illustrated in the accompanying drawings, wherein—

50 Figure 1 is a view illustrating the manner of using the device of my invention for the purpose of reaming the exhaust valve seat of an engine cylinder;

Fig. 2 is a view partly in section and

partly in elevation of the device of my invention; and

Fig. 3 is a detailed sectional view taken on the line 3—3 of Fig. 2 and looking in the direction indicated by the arrows.

Similar characters of reference refer to 60 similar parts throughout the several views.

In Fig. 1 reference letter A illustrates a conventional type of internal combustion engine cylinder provided with the usual beveled exhaust valve seat B and exhaust valve stem guide C, both in the present case being formed in one piece with the cylinder casting. At D, I have illustrated internal threads which are designed to coöperate in the usual manner with the cage which carries the intake valve and its seat. In Fig. 1 these last-mentioned parts and the exhaust valve have been removed for the purpose of permitting access to the exhaust valve seat and the insertion of the valve seat reamer. 75

The tool of my invention consists of an integral stem or shank 5 which is squared at 6 or otherwise conformed at its upper end so that a suitable wrench or other tool may be applied thereto. The lower end of the 80 shank is preferably of reduced diameter, as shown at 5^a, so that the stem may have a working fit in the valve stem guide associated with the valve seat to be reamed. Disposed upon the shank 5 intermediate its 85 ends and secured thereon conveniently by being driven upon the lower end of the larger diameter portion of the shank, is the usual milling tool or reaming cutter 7, the cutting edges 7^a of which face toward the 90 portion 5^a of the shank. The reaming cutter 7 may, of course, be secured in position in any suitable manner, the arrangement shown and described being merely representative. 95

Disposed upon the reduced diameter portion 5^a of the tool shank is an integral sleeve 8, comprising three portions, to-wit: the cylindrical and externally threaded upper portion 8^a, the hexagonal intermediate portion 8^b, and the lower portion 8^c, which tapers downwardly from the hexagonal portion 8^b and is provided with external screw threads. The tapered lower portion 8^c of the sleeve is moreover provided with a plurality of longitudinal slits or saw-cuts 9 so that the sleeve may be secured in any desired position along the shank portion 5^a 105

by means of a clamping nut 10. It will be understood that with the sleeve 8 disposed upon the shank portion 5^a threading of the nut 10 upon the slit tapered lower end 8^a of the sleeve will cause the several tongues constituting said tapered lower end to be forced tightly into engagement with the said shank portion 5^a.

Threaded upon the upper portion 8^a of the sleeve is a cap or nut 11 which is preferably externally milled so that it may be grasped by the fingers and easily telescoped on and off the upper sleeve portion 8^a for a purpose now to be explained.

Let us assume that the improved tool of my invention is to be used for the purpose of reaming the exhaust valve seat B of Fig. 1, the exhaust valve and intake valve cage and parts carried thereby having been removed as illustrated. The parts 8, 10 and 11 having been removed from the portion 5^a of the tool shank, the latter is inserted into the valve stem guides C, as shown in Fig. 1, which, of course, permits the cutting edges of the reaming cutter to come into contact with the seat. Cap 11 is threaded upon the sleeve portion 8^a as far as it will go, or substantially as far as it will go, and the sleeve 8 is placed upon the lower end of the shank portion 5^a and slipped upwardly until cap 11 engages the lower end of the valve stem guide. Nut 10 is then applied securely to retain sleeve 8 in position. Cap 11 is now threaded partially off of the upper sleeve portion 8^a. Since this operation necessarily decreases the distance between the reaming cutter 7 and the cap 11, and since the latter bears against the lower end of the valve stem guide C, the cutting edges of the cutter are caused to bite into the hard film which has been formed on the seat B as previously explained. The cap 11 is turned relatively to the sleeve portion 8^a sufficiently to cause the cutting edges of the reaming cutter to move entirely through this thin film. A wrench or other suitable tool is now applied to the upper portion of shank 5 and the latter, together with the reaming cutter 7, is turned to remove the aforesaid scale or film. The nut 11 being accessible is preferably grasped and turned with the shank when the latter is given the very few turns necessary to remove the said scale or film. After the said scale or film has been removed from the valve seat, the parts 8, 10 and 11 may either be removed or the cap 11 may be threaded down upon the sleeve portion 8^a so that the cap 11 ceases to bear against the valve stem guide. Thereafter such further reaming of the seat as may be necessary or desirable is performed in the usual manner by turning shank 5.

I have found that if the reaming cutter is applied to a valve seat that has been in

use for some time, and merely rotated in the usual manner without removing the scale or film as just explained, the cutting edges of the reaming cutter very quickly become dull. The usefulness of the reaming cutter is thus seriously impaired and the reaming operation is more tedious than when the improvements of my invention are employed. I have found that the cutting edges of the reaming cutter are not appreciably dulled by causing the same initially to cut directly through the thin scale or oxid film as herein described.

Having thus described my invention, what I claim as new and desire to secure by United States Letters Patent, is:

1. A valve seat reaming tool of the class described comprising a shank carrying a reaming cutter intermediate its ends, that portion of the shank below the cutter being adapted to be inserted in the valve stem guide associated with a valve seat to be reamed, and devices on said shank below said cutter arranged to cooperate with the valve stem guide to cause the cutter edges to bite into the seat, said devices comprising a sleeve disposed around said shank, said sleeve provided with a cylindrical screw threaded upper portion and an externally threaded and slit conical lower portion, a clamping nut cooperating with said conical lower portion arranged to retain said sleeve at any one of a plurality of positions on said shank, and a cap threaded upon the upper portion of said sleeve arranged to bear against the lower portion of the valve stem guide for the purpose set forth.

2. A valve seat reaming tool comprising a shank carrying a reaming cutter intermediate its ends, that portion of the shank below the cutter being adapted to be inserted in the valve stem guide associated with the valve seat to be reamed, and devices on said shank below said cutter arranged to cooperate with the valve stem guide to cause the cutter edges to bite into the valve seat, said devices comprising a sleeve disposed around said shank, means for retaining said sleeve at any one of a plurality of positions on said shank, and an adjustable cap threaded on said sleeve and arranged to bear against the valve stem guide for the purpose set forth.

3. A valve seat reaming tool comprising a shank carrying a reaming cutter intermediate its ends, that portion of the shank below the cutter being adapted to be inserted in the valve stem guide associated with the valve seat to be reamed, a removable sleeve arranged to be slipped over the lower end of said shank, means for securing said sleeve at any one of a plurality of positions on said shank, and a device adjustable with respect to said sleeve arranged to bear against the valve stem guide to cause the

cutter edges to bite into the seat for the purpose set forth.

4. A valve seat reaming tool comprising a reaming cutter provided with a shank adapted to be inserted in the valve stem guide associated with the valve seat to be reamed, a removable member adapted to be applied to the lower end of said shank, means for securing said removable member at any one of a plurality of positions on said shank, and a device adjustable with respect to said movable member adapted to bear against the valve stem guide to cause the cutter edges to bite into the valve seat for the purpose set forth.
5. A valve seat reaming tool comprising a reaming cutter provided with a shank adapted to be inserted in the valve stem guide associated with the valve seat to be reamed, a removable sleeve adapted to slip over the lower end of said shank, means for retaining said sleeve at a plurality of positions on said shank, and a nut threaded on said sleeve and adapted to bear against the valve stem guide to cause the cutter edges to bite into the valve seat for the purpose set forth.

6. A valve seat reaming tool of the class described comprising a shank, a reaming cutter carried by said shank, said shank adapted to be inserted in the valve stem guide associated with the valve seat to be reamed, and devices on said shank arranged to cooperate with the valve stem guide to cause the cutter edges to bite into the seat, said devices comprising an integral sleeve disposed around said shank, said sleeve comprising a cylindrical screw-threaded upper portion, a central nut and an externally screw-threaded and slit conical lower portion, a clamping nut coöperating with said conical lower portion arranged to retain said sleeve at any one of a plurality of positions on said shank, and a cap threaded upon the upper portion of said sleeve arranged to bear against the lower portion of the valve stem guide for the purpose set forth.

In witness whereof, I hereunto subscribe my name this 15 day of December, 1919.

FRANS O. ALBERTSON.
